UNITED STATES PATENT OFFICE

HENRY W. DE JARRETTE, OF DES MOINES, IOWA, ASSIGNOR OF ONE-HALF TO JOHN C. HOL, OF DES MOINES, IOWA

INK-DISTRIBUTOR-ROLLER STRUCTURE

Application filed August 19, 1929. Serial No. 386,936.

The object of my present invention is to provide an ink distributor roller structure of improved design, the details of the present device being a substantial improvement over the ink distributor illustrated in my Patent No. 1,698,123, issued January 8, 1929. A further object is to provide means for supporting and actuating an ink distributor roller, such means being of simple durable 10 and comparatively inexpensive construction.

More particularly, it is my object to provide bearing structures for an ink distributor roller including a novel means of adjustment for adjusting the bearing structures relative to their respective supporting devices.

Another object is to provide improved means for actuating a swinging bearing from an oscillatable shaft.

With these and other objects in view my 20 invention consists in the construction, arrangement and combination of the various parts of my device, whereby the objects contemplated are attained, as hereinafter more fully set forth, pointed out in my claims, and 25 illustrated in the accompanying drawings, in which:

Figure 1 is a plan view of a printing press illustrating my improved type of ink distributor roller associated therewith.

30 Figure 2 is an enlarged sectional view on the line 2—2 of Figure 1, showing the ink distributor roller in one position.

Figure 3 is a similar view, showing the ink distributor roller in another position.

35 Figure 4 is an enlarged sectional view on the line 4—4 of Figure 3; and

Figures 5, 6, 7 and 8 are detail sectional views on the lines 5—5, 6—6, 7—7 and 8—8 respectively of Figure 4.

40 On the accompanying drawings, I have used the reference numerals 10 and 12 to indicate the side frames of a printing press. The printing press herewith illustrated is the type in which a transverse ink roller 14 and a plurality of angularly disposed ink distributor rollers 16 are journaled on the side frames 10 and 12.

The ink roller 14 is actuated for rotation by means not herein disclosed.

50 My ink distributor roller structure con-

sists of a roller A having one end universally and slidably mounted in a bearing structure B and its other end universally mounted in a bearing structure C, which is movable. The roller A is free to rotate.

The stationary bearing structure B is adapted for mounting on the side frame 10 of the printing press and the movable bearing structure C is secured to a rock shaft 18 carried by a bracket 20 secured to the side frame 12 of the printing press.

The bearing structures B and C each consist of a bearing member 22 of a sleeve-like construction having a hemispherical socket in its upper end. A cap 24 is provided for each bearing member 22 and has a similar hemispherical socket.

The sockets just referred to are adapted to receive ball members 26 and 28. The ball member 26 is provided with a bore through which one end of a roller shaft 30 is slidably and rotatably mounted. The ball 28 is formed on or secured to the other end of the shaft 30. The ball 28 and the ball 26 are both rotatably mounted in their respective bearing members 22.

A sleeve member 32 is rotatably received in each bearing member 22. Each sleeve member 32 is provided with an angular head 34, whereby the sleeve member may be 80 rotated. An annular groove 36 is cut in each sleeve member 32 and a stud 38 screw threaded or driven into the bearing member 22 is received in such groove for allowing rotation of the sleeve member 32 relative to 85 the bearing member 22, but preventing longitudinal movement of one relative to the other.

Another annular groove 40 is cut in the outer surface of each sleeve member 32 with which a set screw 42 may coact without 90 damaging the outer surface of the sleeve member 32 when the set screw is tightened.

Each sleeve 32 is internally screw threaded and one sleeve coacts with a supporting rod 44, which is likewise screw threaded, while 95 the other coacts with a supporting rod 46. The supporting rod 44 is formed on a foot 48 having slots 50. Bolts 52 extend through the slots 50 and into the frame member 10 of the printing press.

The supporting rod 46 terminates in a split head 54 adapted to be clamped by a screw 56 to the outer end of the rock shaft 18.

The bracket 20, in which the rock shaft 18 is journaled, has an elongated sleeve 58, one end of which extends through an opening 60 in the frame member 12, whereby a long bearing is provided for the rock shaft 18.

As best shown in Figure 8, the bracket 20 is provided with a hole 62 through which a bolt 64 extends for bolting the bracket 20 against the side of the frame member 12. The frame member 12 is usually provided with ribs 66 with which flanges 68 of the bracket 20 may coact for holding the bracket in alignment.

The inner end of the rock shaft 18 is provided with a head 70 having a slot 72 therein. A block 74 is adapted to slide longitudinally 20 in the slot 72. The block 74 is pivoted on a pin 76 having a square portion 78. The square portion 78 extends through a slot 80 formed in an arm 82.

A clamping nut 84 is associated with the 25 outer end of the pin 76 (which is screw threaded) for clamping the shoulder formed by the round portion of the pin 76 which is mounted in the block 74 against one side of the arm 82.

The arm 82 has its lower end seated against 30 a rock shaft 86 mounted on the printing press and a cap 88 is associated therewith. The cap 88 is securely clamped to the arm 82 by means of bolts or screws 90 and a set screw 92 prevents turning of the arm 82 relative to the shaft 86. The shaft 86 is part of the printing press and is ordinarily driven by a reciprocable link 94 connected with an arm 96. The arm 96 is secured to the shaft 86. Each end of the shaft 86 is provided with an 40 ink roller arm 98 adapted to support an ink roller 100.

In the operation of the device, the ink roller 100 is adapted to assume the position shown in Figure 2 for collecting ink from the ink 45 roller 14. The roller 100 then swings upwardly, as shown in Figure 3, so that a printing bed 102 traveling thereunder will collect ink therefrom.

The angularly arranged rollers 16 serve in 50 a measure to distribute the ink on the printing bed 102 as the printing bed travels in a left hand direction under the rollers 16, but in actual practice does not evenly distribute it.

It has therefore been my object to provide 55 the ink distributor roller A having one end universally mounted in a stationary bearing and its other end mounted in a movable bearing so that the roller A, by moving to an angular position, can contact with one of the 60 rollers 16, as shown in Figure 1 or can be moved to a directly transverse position for contacting with the roller 100, as shown in dotted lines in Figure 1.

The operation and advantages of this roller 65 are fully set forth in my former patent.

The present invention has to do with the improvements in design, whereby the device is easily adjusted to different printing presses and may be accurately adjusted for proper operation after being installed.

For instance, the height of the bearings B and C may be easily adjusted by loosening the set screws 42 and turning the sleeve members 32 in the desired direction and the desired amount for raising or lowering the bearings.

The foot 48 of the stationary bearing B may be adjusted relative to the frame 10 because of the slot connection 50. The movable bearing C may be adjusted circumferentially 80 with respect to the rock shaft 18 by loosening the clamping bolt 56.

The amount of throw imparted to the supporting rod 46 may be varied by adjusting the pivot pin 76 longitudinally relative to the slot 80 in the arm 82 and the arm 82 itself may be adjusted around the oscillatable shaft 86 as desired.

The clamping nut 84 and the pin 76 may be loosened so that the block 74 can be shifted up or down to lengthen or shorten the throw of the roller A. It will be obvious that thus shifting the block 74 changes both the operating radius of the arm 82 and the head 70. These adjustments can be made without disassembling any of the parts of the device, as was found necessary in the construction illustrated in my former patent.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In an ink distributor roller structure, a stationary bearing for one end of an ink distributor roller, a movable bearing for the other end thereof, a shaft for the second bearing, said second bearing being secured to said shaft and means for oscillating said shaft comprising a swinging arm, and a second arm having a sliding connection with the first arm and secured to said shaft.

2. In an ink distributor roller structure, a stationary bearing for one end of an ink distributor roller, a movable bearing for the other end thereof, a shaft for the second bearing, said second bearing being secured to said shaft and means for oscillating said shaft comprising a swinging arm, a second arm secured to said shaft, and a slot and sliding block connection between said arms.

3. For use with a frame and an oscillatable shaft journaled thereon, a roller shaft, a bearing member for each end thereof, a supporting member for each bearing member, a sleeve interposed between each bearing mem-

ber and its respective supporting member, each sleeve being rotatable relative to one member and screw threaded relative to the other, one of said supporting members being 5 stationarily mounted on said frame and the other one movably mounted, a rock shaft for the movable supporting member, said last mentioned member being clamped to the rock shaft, an arm adapted to be attached to said 10 oscillatable shaft and a sliding block and slot connection between said arm and said rock shaft.

4. For use with a frame and an oscillatable shaft journalled thereon, a roller shaft, a 15 bearing member for each end thereof, a supporting member for each bearing member, a sleeve interposed between each bearing member and its respective supporting member, each sleeve being rotatable relative to one 20 member and screw threaded relative to the other, one of said supporting members being stationarily mounted on said frame and the other one movably mounted, a rock shaft for the movable supporting member, said last 25 mentioned member being clamped to the rock shaft, an arm adapted to be attached to said oscillatable shaft, a slotted head on said rock shaft and a block pivoted to said arm and slidable in the slot of said slotted arm.

5. For use with a frame and an oscillatable shaft journalled thereon, a roller shaft, a bearing member for each end thereof, a supporting member for each bearing member, a sleeve interposed between each bearing member 35 and its respective supporting member, each sleeve being rotatable relative to one member and screw threaded relative to the other, one of said supporting members being stationarily mounted on said frame and the 40 other one movably mounted, a rock shaft for the movable supporting member, said last mentioned member being clamped to the rock shaft, an arm adapted to be attached to said oscillatable shaft, a slotted head on said rock 45 shaft and a pin longitudinally adjustable on said arm, and a pivoted block on said pin adapted to slide in the slot of said slotted arm.

Des Moines, Iowa, July 26, 1929.

HENRY W. DE JARRETTE.
